(57) **CLAIM**

The ornamental design for a confinement liner for a substrate processing chamber, as shown and described.

DESCRIPTION

FIG. 1 is a top isometric view of a confinement liner for a substrate processing chamber showing my new design; FIG. 2 is a top plan view thereof; FIG. 3 is a bottom plan view thereof; FIG. 4 is a front elevation view thereof; FIG. 5 is a rear elevation view thereof; FIG. 6 is a left side elevation view thereof; FIG. 7 is a right side elevation view thereof; and, FIG. 8 is an enlarged cross sectional view taken along line 8-8 of FIG. 2.

The broken lines shown in the drawings represent portions of a confinement liner for a substrate processing chamber that form no part of the claimed design.
